UNITED STATES PATENT OFFICE.

WALTER B. NOYES, OF BUFFALO, NEW YORK, ASSIGNOR TO THE CHICAGO ROLLER SPRING COMPANY, OF CHICAGO, ILLINOIS.

BED-BOTTOM.

SPECIFICATION forming part of Letters Patent No. 381,024, dated April 10, 1888.

Application filed April 1, 1887. Serial No. 233,289. (No model.)

To all whom it may concern:

Be it known that I, WALTER B. NOYES, of the city of Buffalo, in the county of Erie and State of New York, have invented new and useful Improvements in Bed-Bottoms, of which the following is a specification.

This invention relates to an improvement in that class of bed-bottoms which are composed of a series of flexible straps arranged lengthwise of the bed and secured to a transverse roller which is provided with a ratchet mechanism for taking up any slack of the straps.

The object of my invention is to improve the construction of this class of bed-bottoms by providing the bed-bottom with a spring-roller, whereby the straps are held taut at all times and the strain more uniformly divided throughout the straps or slats of the bed-bottom.

My invention consists of the improvements which will be hereinafter described, and pointed out in the claims.

In the accompanying drawings, consisting of two sheets, Figure 1 is a longitudinal sectional elevation of my improved bed-bottom. Fig. 2 is a top plan view thereof. Fig. 3 is a sectional elevation in line $x-x$, Fig. 1, on an enlarged scale. Fig. 4 is a sectional elevation of the actuating pawl-lever, taken in line $x-x$, Fig. 3. Fig. 5 is a top plan view of the same. Figs. 6, 7, and 8 are cross-sections in lines $y-y$, $z-z$, and $w-w$, Fig. 3, respectively. Fig. 9 is a cross-section taken in line $x-x$, Fig. 2, showing the manner of securing the straps at the foot of the bed. Fig. 10 is a sectional top plan view thereof. Fig. 11 is a front elevation of one of the springs which support the straps at the foot of the bed. Fig. 12 is a sectional elevation showing the end of one of the straps or slats secured to the foot of the bed without a spring.

Like letters of reference refer to like parts in the several figures.

A represents the head-board of a bedstead; A', the foot-board, and A² A³, the side rails or boards connecting the head and foot boards and provided with sills a, upon which the transverse wooden slats a' are supported in the usual manner.

B represents the metal straps which form my improved bed-bottom and which extend longitudinally from the head to the foot of the

bed. The straps B are fastened at one end to a cross-bar, C, which is secured to the side rails, A², near the foot-board by brackets D. The opposite ends of the straps B are fastened to a cylindrical drum or roller, E, arranged between the side rails in front of the head-board A. The roller E is preferably constructed of metal tubing, and is provided at one end with an extension-piece, E', which is of smaller diameter than the roller, so as to fit snugly in the bore of the roller. The extension-piece E' is secured to the roller E by a screw, e, which engages in one of a series of screw-holes, e', formed in the extension-piece E'. The extension-piece E' permits the roller to be lengthened or shortened, according to the width of the bed, and enables the roller to be adjusted to fit between the side rails of beds of different widths. The outer end of the extension-piece E' is closed, and is provided with a journal, e', which rests in a bearing, f, formed in a bracket, F, secured to the rail A². The portion of the extension-piece extending outside of the roller is provided with a sleeve, g, which is of the same diameter as the roller, and is secured to the roller by a screw, g', which engages in one of a series of holes, g², formed in the extension-piece E'. The strap B at that end of the bed-bottom is fastened to the sleeve g by the screw g', which secures the sleeve to the extension-piece E'. The opposite end of the roller E is closed by a cap, H, having a rim, h, projecting inside of the roller, and is secured thereto by screws or other suitable means.

The cap H is provided with a central hollow hub, h', formed on the outside of the cap, and through which passes loosely a shaft, I, which forms the journal upon which this end of the roller turns. The outer end of the shaft I is journaled in a bearing, j, formed in a bracket, J, secured to the side rail, A².

k represents a collar or sleeve surrounding the outer end of the shaft I, and secured thereto by a key, k', or other suitable means, so as to turn with the shaft. The sleeve or collar k is provided at its inner end with a cap, K, which incloses the hub h' of the cap H.

l represents a pawl pivoted to the inside of the cap K and adapted to engage in a notch or recess, l', formed in the hub h', as shown in

Figs. 3 and 7. The pawl l is provided with a curved or beveled face, l' , and an abrupt face, l'' , which permits the pawl to slide over the hub h' without engaging in the notch l' when the shaft is turned in one direction and to drop into the notch and lock the roller to the shaft when turned in the opposite direction.

5 M represents a series of spiral springs arranged inside of the roller E and surrounding the shaft I . The springs M are each secured at one end to the shaft I , and are provided at their opposite ends with a loop, m , which engages over a rod, n , arranged in line with the shaft. The rod n is arranged between the shaft and the inner surface of the roller, and forms part of a frame, N , which is secured to the inner surface of the roller E , so as to turn therewith. The frame N is provided at its opposite ends and near its center with concentric 15 plates or disks n' , to which the rod n is secured. The plates n' also form bearings for the shaft I , which turns in central openings formed in the plates.

20 p represents a ratchet-wheel formed on or secured to the outer end of the sleeve k ; and P represents a pawl-lever surrounding the ratchet-wheel and provided with a pawl, p' , which engages with the teeth of the ratchet-wheel p .

25 q represents a ratchet-wheel formed on or secured to the sleeve k , and q' represents a pawl pivoted to the bracket J and engaging with the ratchet-wheel q .

30 The springs M are wound or coiled around the shaft by turning the shaft by means of the pawl-lever P and ratchet-wheel p , and the pawl q' , engaging with the ratchet-wheel q , locks the shaft from turning in the opposite direction to uncoil the springs. Upon locking 35 the shaft I by the ratchet-wheel and pawl q' the tension or strain on the springs is transmitted to the roller E and the straps B . The springs M are wound sufficiently tight until the proper tension is given to the roller to hold the straps taut and sustain the required 40 weight on the bed-bottom. The cap K , carrying the pawl l , turns with the shaft I as the latter is rotated, and the inclined or beveled face of the pawl permits the pawl to slide over 45 the notch l' of the hub h' without engaging therein. Upon removing the roller E from the brackets the ratchet-wheel q is released from the pawl q' , and the springs are prevented from uncoiling by the pawl l engaging in the 50 notch l' of the hub h' . The ratchet-wheel p and lever P permit the tightening or coiling of the springs to increase their tension on the roller without removing the roller from the brackets, and the pawl l , engaging in the 55 notch l' , prevents the springs from uncoiling when the roller has been removed from the brackets. The straps or slats B are all of uniform length, and are preferably fastened to the roller by screws u , which pass through openings formed in the ends of the straps and engage in screw-holes formed in the roller on a line drawn parallel with the sides of the roller.

The ends of the springs attached to the rod n are free to slide on the rod, as the springs are coiled around the shaft, which prevents the 70 springs from being twisted out of shape. Any number of springs may be employed as may be desired to increase the tension of the roller, and as the tension is uniform throughout the length of the roller the strain is divided 75 equally on all the straps.

The straps B are secured to the lower cross-bar, C , by screw-bolts R , which are inserted through openings in the cross-bar, and are provided with screw-nuts r , which bear against 80 the rear side of the cross-bar. The inner ends of the bolts R are each provided with a hook, r' , which engages with a coil-spring, S , fastened to the end of each strap B . The springs S assist in holding the straps B taut, and the 85 screw-bolts R permit any slack or unevenness in the length of one or more of the straps to be taken up independently of the other straps.

If desired, the springs S may be dispensed with and the bolts R be provided with a loop 90 to which the straps are secured, as shown in Fig. 12.

95 T represents one or more straps fastened to the under side of the roller E and connected to the lower cross-bar, C , by a spiral spring, t . The straps are arranged below the straps B and draw upon the roller E in an opposite direction to the straps B , so as to increase the tension on the roller when an additional weight is applied to the straps B .

100 If desired, the lower cross-bar, C , may form part of an independent frame supported on the wooden slats a' of the bed and fitting between the head and foot boards and sidestrips of the bed, the brackets in this case being secured to the side strips of the independent frame, instead of being secured to the side 105 straps of the bedstead.

I claim as my invention—

110 1. In a bed-bottom, the combination, with the side rails, bottom cross-bar, C , spring-roller E , and flexible straps B , connecting the roller E with the bottom cross-bar, of an extension-piece, E' , adjustably secured to the roller, whereby the roller can be lengthened or 115 shortened, substantially as set forth.

120 2. The combination, with the roller E , shaft I , and springs M , surrounding said shaft and connecting the roller with the shaft, of a cap, H , secured to the roller and provided with a hub, h' , forming a journal for the shaft, a collar, k , secured to the outer end of the shaft, and a cap, K , formed with the collar k and provided with a pawl, l , adapted to engage in a notch, l' , formed in the hub h' of the roller, substantially 125 as set forth.

130 3. In a bed-bottom, the combination, with the hollow roller E , and a frame, N , secured to the inner surface of the roller, and provided with a rod, n , of a central shaft, I , mounted in bearings in the frame N , and springs M , surrounding the shaft I , and secured at one end to the shaft and provided at their opposite end with a loop, m , which engages over

the rod *n* of the frame *N*, substantially as set forth.

4. In a bed-bottom, the combination, with the side rails, bottom cross-bar, *C*, and a roller, *E*, journaled in brackets secured to the side rails, of a series of flexible straps, *B*, secured at one end to the roller *E* and at their opposite end to the bottom cross-bar, and flexible straps *T*, secured at one end to the roller *E*, be-

low the straps *B*, so as to turn the roller *E* in *10* an opposite direction to the straps *B*, and connected at their opposite ends to the cross-bar *C* by springs *t*, substantially as set forth.

Witness my hand this 19th of March, 1887.
